US00D848070S

(12) **United States Design Patent** (10) Patent No.: **US D848,070 S**
(45) Date of Patent: **** May 7, 2019**

(54) **RAZOR**

(71) Applicant: **Park Seung Bok**, Incheon (KR)

(72) Inventor: **Park Seung Bok**, Incheon (KR)

(**) Term: **15 Years**

(21) Appl. No.: **35/503,427**

(22) Filed: **Apr. 28, 2017**

(80) **Hague Agreement Data**

Int. Filing Date: **Apr. 28, 2017**

Int. Reg. No.: **DM/096925**

Int. Reg. Date: **Apr. 28, 2017**

Int. Reg. Pub. Date: **Jul. 28, 2017**

(51) **LOC (11) Cl. 28-03**

(52) **U.S. Cl.**

USPC **D28/46**

CPC **B26B 21/24** (2013.01)

(58) **Field of Classification Search**

USPC D28/46-48

CPC B26B 21/24

See application file for complete search history.
